(57) **CLAIM**

The new ornamental design for an imaged elastic retaining band, as shown and described.

DESCRIPTION

FIG. 1 is a planar view of the new design for an imaged elastic retaining band stretched around a pack of credit cards shown in dotted lines, the imaged elastic retaining band having a slider with an imaged area thereon;

FIG. 2 is a planar view of the new design for an imaged elastic retaining band stretched around a wad of currency shown in dotted lines, the imaged elastic retaining band having a slider with an imaged area thereon;

FIG. 3 is a planar front view of the imaged elastic retaining band of FIGS. 1 and 2 in a relaxed state;

FIG. 4 is a planar rear view of the new design for the imaged elastic retaining band showing the back side of the elastic band and the back side of the slider thereon;

FIG. 5 is an enlarged end view of one end of the slider shown in FIGS. 1-4, the end view of the other end of the slider being the same; and,

FIG. 6 is an enlarged side view of the slider shown in FIGS. 1-5, the side view of the other side of the slider being the same.

The broken lines are for illustrative purposes only and form no part of the claimed design.
